DESIGN FOR AN APPLIQUÉ EMBLEM OR SIMILAR ARTICLE FOR WEARING AP- PAREL

Charles Emmey, New York, N. Y.

Application July 31, 1936, Serial No. 64,163

Term of patent 7 years

To all whom it may concern:

Be it known that I, Charles Emmey, a citizen of the United States, residing in the city of New York and county of New York, State of New York, have invented a new, original, and ornamental Design for an Appliquéd Emblem or Similar Article for Wearing Apparel, of which the following is a specification, reference being had to the accompanying drawing, forming part thereof.

In the accompanying drawing forming a part hereof, the figure is a plan view of an appliquéd emblem or similar article for wearing apparel.

Said design as shown is of no appreciable thickness.

I claim:

The ornamental design for an appliquéd emblem or similar article for wearing apparel, substantially as shown and described.

CHARLES EMMEY.
